SHAPER DUST HOOD

Fred I. Johnson, Sheboygan, Wis., assignor to
Reiss Manufacturing Corporation, Wilmington,
Del., a corporation of Delaware

Application January 27, 1949, Serial No. 73,202

7 Claims. (Cl. 144—252)

1

This invention relates to an improved dust collecting hood employing an air suction system for removing dust or shavings produced by wood working machinery such as routers, hand shapers and other vertically operating shapers and cutters.

An object of this invention is to provide a dust collecting hood of the type described which will catch the shavings thrown off by this type of machinery at the source before they have a chance to become scattered and interfere with the cutting or shaping operation being carried out.

Furthermore, it is an important object that the hood opening be small enough to cooperate automatically with the contour of the workpiece in such a way that a high efficiency of suction pick-up may be obtained.

It is a further object of this invention to provide a dust collecting hood of a simple and compact design which may be easily adjusted and adapted to the various automatic shapers employed in the woodworking industry.

Still further objects of this invention will become apparent from the detailed description given hereafter in connection with the attached drawings, in which:

Figure 1 is a top plan view of the dust hood;

Figure 2 is a side elevational view of the hood of Figure 1;

Figure 3 is a fragmental detailed view taken along the line 3—3 of Figure 2, and

Figure 4 is a perspective view of an automatic shaper with the improved hood in its assembled relationship.

In order to more completely describe applicant's improved dust collecting hood, reference will now be had to Figures 1 through 3, inclusive, in the drawings, wherein the dust collecting hood comprises an enclosure generally designated as 10 having a top 11, a bottom 12, ends 14 and 15, and a rear 18, which are preferably made of sheet metal. Top and bottom 11 and 12, respectively, are identical in shape and have a substantially U-shaped recess 13 formed in the front edge of each. Fixed to the ends of the top and bottom plates and holding them in spaced parallel relationship, by means such as welding, are the two curved end wall members 14 and 15, preferably of a shape as shown in the drawings. Cylindrical air exhaust ducts 16 and 17 are fixed to end wall members 14 and 15, respectively, and are connected with the interior of hood 10 by means of an opening in each of the end walls. Wall 18 is

curved to fit the contour of the rear sides 19 of top and bottom plates 11 and 12 and forms the supporting means for the top and bottom plates along with end wall members 14 and 15, on three sides. The front side 20 of the hood is open for the purpose hereinafter described.

Adjustable hood gate 21 forms part of the front edge of the side wall 15 and is fastened thereto by means of hinge 22 and a hinge fastening means such as metal screws 23. In order that the hood gate's length may be adjusted, it is made of two relatively adjustable rectangular members 24 and 25. Two parallel slits 26 are provided in member 25 for the purpose of this adjustable feature and by the means of two adjustable screws 27 cooperating in these slits and received by member 24, the length of the hood gate may be extended or retracted as desired. Two arcuate spring members 28, fastened on the inside of end wall 15, in the position shown, by screws 29, act as a stop to prevent the hood gate from swinging inwardly into the hood beyond a desired adjustable limit.

A rectangular-shaped flexible tongue 30, made of leather, rubber or other suitable material, is fixed along one of its longer sides to the entire length of the front edge of end wall 14 by any suitable fastening means such as metal screws and washers 31.

30. A pivot post 32 is fixed perpendicularly to the underside of bottom plate 12, as shown, by means of nut 33 on a reduced screw threaded end 34 of one end of the post, which is received by hole 35. The other end 36 of the post is a reduced end thus providing a stop shoulder 37 for pivotally supporting the hood 10.

At a point on the front of the base 12, near the point at which side wall 14 is fixed to base 12, as shown in Figure 2, is fixed a hood take-up support, generally designated as 39. This member consists of a flat plate mounting means 40, fixed to the bottom of base 12 by means of screws 41, a hood take-up pivot post 42 fixed vertically to the bottom of the mounting means 40, a cylindrical take-up roller 43 received by an opening therein by the pivot post 42, a sealed roller bearing 44 received by the pivot post and rotatably supporting roller 43, a rod 45 rotatably received by means of an eye 46 on post 42 below the bearing 44, and a take-up slide cap 47, fixed to the end of post 42 and holding members 45, 44 and 43 in assembled relationship.

An angle bracket member 48, having a hole 55 through its vertical portion 49, fits on to rod 45

and forms part of the hood take-up support along with spring 52. In the horizontal portion of the angle bracket 48 are two holes for receiving bolts 51 by which the bracket is fixed to the hood supporting surface described hereinafter. About rod 45 is the coiled tension spring 52 having one end fixed in notch 53 in the vertical portion 49 of bracket 48 and the other end fixed to the end 54 of rod 45 by means of two nuts 55 and 56 screw threaded on end 54.

A sash stop chain 57 is fixed at end 58 to the wall 18 and is received as desired along its length by notch 59 in the vertical portion 49 of bracket 48.

A follower cleaner 60, preferably made of spring metal and having felt pads 61 fixed at one end, is positioned within the hood 10 as shown in Figure 1 by the fastening means 62.

In Figure 4, the hood 10 is shown in its assembled relationship with an automatic shaper generally designated as 63. This automatic shaper utilizes a climb cut principle which is common in the milling machine art, the stock 64 being held in jigs which are driven past the cutter spindle 65 at a constant rate of feed by means of a sprocket on the cutter head spindle which engages a chain on the lower part of the form. The forms are ordinarily four-sided and clamp a piece of stock such as a chair leg in four different positions so that all four sides of the piece may be machined. The form or jig carrying the stock is held in engagement with the cutter head and the drive sprocket by means of an air cylinder, generally designated as 66, which forces the workpiece forward. It is, of course, to be understood that the particular automatic shaper 63, the full details of which are not shown since it forms no part of this invention, is shown for purposes of illustrating the uses of hood 10. This hood may be, however, utilized with many other types of woodworking machines, such as routers, hand shapers, etc., and it is not limited in its use to the particular Whitney automatic shaper shown.

The pivot post 32 of hood 10 is positioned in a hole provided vertically in the shaper table 67 at a position such that the U-shaped recesses 13 of the top and bottom plates closely fit about the rear half of the spindle 65 in such a position as to receive the shavings or dust thrown off by the cutter without allowing them to be scattered about and, at the same time, without permitting the loss of efficiency in the air suction pick-up which is provided by a suitable exhaust pump connected to the Y-connector 68 which, in turn, leads by means of flexible tubes 69 and 70 to the exhaust ducts 16 and 17 provided in the end walls of the hood 10.

The end of the hood opposite the first pivot post is slidably supported on the table by means of the hood take-up support 39 whose rod 45 is held in position by means of bracket 48 fixed to top 67 by means of bolts 51.

It is seen that the spring 52 urges end 14 of the hood 10 towards the workpiece 64 by pivoting the hood about the pivot post 32. As the contour of the work changes, the take-up roller 43, urged by spring 52, follows this change in contour and, therefore, holds the end 14 of the hood as close as possible to the workpiece. Flexible tongue 30 is provided in order to form a close seal with the workpiece and, at the same time, to prevent the workpiece from being scarred or otherwise injured by the hood as the wood passes across the cutter spindle.

Adjustable hood gate 21 may have its length extended in order to properly receive the trailing edge of the workpiece without the loss of the efficiency of the air suction system. In the case of thin stock, such as table tops, which may extend a considerable distance beyond the edge of the form before passing by the cutter head, this sliding plate 25 can be notched so that the stock may pass through it. This does not materially affect the efficiency of the dust hood.

A safety sash chain 57 is provided, as pointed out supra, in order to provide a limit beyond which the hood end 14 cannot be urged pivotally about pivot post 32. This, of course, prevents the hood from jamming with the spindle 65 after the workpiece has been fed completely by the cutter.

The follower cleaner 60 described above is for the purpose of continuously cleaning a guide collar located on the cutter spindle, against which the wooden form or jig presses as it is driven past the cutter spindle.

From the foregoing description of the improved hood and the method of assembling it with relation to a woodworking machine, it is readily seen that applicant's type of hood has overcome the difficulties encountered when employing the usual large canopy type hood. Applicant's particular hood is not only small and compact in design, but also offers an improved means for picking up the shavings at their source and, at the same time, requires a less expensive type exhaust system for removing the shavings to an out of the way discarding position, since it provides an effective sealing means about the cutter and between the cutter and the workpiece being fed across the spindle thus presenting a minimum clearance for the escape of shavings. Furthermore, the hood is positive in action and follows the contour of a workpiece exactly, without offering mechanical difficulties, such as jamming encountered in the type of hoods previously used in the art.

It is to be understood that the hood may be modified, if desired, by hinging it at the center and making one side rigid, or by hinging it in the center and providing each end of the hood with a spring urged hood take-up support, or by a combination of other pivoted means which would employ the basic idea incorporated in applicant's new and novel hood.

The terminology used in the specification is for the purpose of description and not for limitation; the scope of the invention being defined in the claims.

I claim:

1. An improved dust collecting device comprising a hood enclosure having top, bottom, rear and end plates, an air exhaust duct connected to at least one of said end plates, aligned U-shaped recesses formed in the front edges of the top and bottom plates, a pivot post and a hood take-up support means, each fixed to the underside of the bottom plate and each located on opposite sides of the said U-shaped recess, said hood take-up support being adapted to move said hood enclosure about the axis of said pivot post.

2. An improved dust collecting device comprising a hood having top and bottom plates, the front edge of each having aligned U-shaped recesses formed therein, end plates, a back plate, an air exhaust duct connected to at least one of said end plates, a pivot post fixed to the underside of said bottom plate and to one side of the U-shaped recess, and a hood take-up support

fixed to the bottom plate at the other side of the U-shaped recess, said hood take-up support being adapted to move said hood enclosure about the axis of said pivot post, said hood take-up including a rod fixed rotatably at one end of said take-up support, said rod having a supporting bracket slidably held thereon and a coil spring surrounding said rod, one end of said spring being fixed to said bracket and the other end being fixed to the other end of the said rod.

3. An improved dust collecting hood, as set forth in claim 1, wherein the end plate adjacent the fixed pivot post is provided with a hinged adjustable gate.

4. An improved dust collecting device, as set forth in claim 1, wherein a rectangular flexible tongue is fixed along the leading edge of the end plate which is adjacent the hood take-up support.

5. An improved dust collecting device, as set forth in claim 1, wherein a follower cleaner is provided within the hood and is supported by the black plate.

6. An improved dust collecting device comprising a hood having top and bottom plates, the front edge of each having U-shaped recesses formed therein, two end wall plates, at least one of which has an air exhaust duct connected thereto and a back wall plate, each positioning the top and bottom plates in spaced parallel relationship, said hood being open at the front side, a first pivot post fixed to the underside of the bottom plate and to one side of the U-shaped recess, and a second pivot post fixed at one end on the underside of said bottom plate and at the other side of the said recess, said second post 35

having a take-up roller and a rod mounted rotatably thereon, and a take-up slide cap fixed to the other end thereof, said rod having a supporting bracket slidably mounted thereon and a coiled spring about said rod urging said bracket towards the second post, one end of said spring being fixed to said bracket and the other end being fixed to the second end of said rod.

7. In a woodworking machine of the type having a cutter mounted on a vertical spindle and a work supporting table, the improvement which consists of a dust collecting hood having top, bottom and rear walls, ends open at the front, U-shaped recesses formed in the front edges of the top and bottom walls and adapted to partially enclose the vertical spindle, said hood being provided with a pivot post fixed to the underside of said bottom and to one side of said U-shaped recess, means in said table for receiving said pivot post, and means for slidably supporting said hood at a position on the other side of said last-named U-shaped recess.
